(57) **ABSTRACT**

A *chrysanthemum* plant named 'Zanmulisa' characterized by its large sized daisy-type blooms with bright purple ray florets and prolific branching; and a response time of 7 weeks.

3 Drawing Sheets

1

Botanical designation: *Chrysanthemum×morifolium* Ramat.
Cultivar denomination: 'Zanmulisa'.

BACKGROUND OF THE INVENTION

The present invention relates to a new and distinct cultivar of *chrysanthemum* plant, botanically known as *Chrysanthemum×morifolium* Ramat., and hereinafter referred to by the cultivar denomination 'Zanmulisa'. 'Zanmulisa' is a product of a breeding and selection program for pot mums which had the objective of creating new cultivars with a daisy type inflorescence with medium plant height and a response week of 7 weeks. 'Zanmulisa' is a seedling resulting from a cross of the female parent id 44275 and the male parent id 20560. Plants of the new cultivar 'Zanmulisa' differ from plants of the female parent in inflorescence color; the female parents has red inflorescences, while the seedling has pink ones. Plants of the new cultivar 'Zanmulisa' differ from plants of the male parent in the following characteristics. (1) Inflorescence size. And (2) Response time. (1) The inflorescences of the male parent are smaller than those of the seedling. (2) The response time of the male parent is higher than that of the seedling.

The new and distinct cultivar was discovered and selected as a flowering plant within the progeny of the stated cross by Wilhelmus Bernardus Blom in a controlled environment (greenhouse) in Rijsenhout, The Netherlands in May 2006. The first act of asexual production of 'Zanmulisa' was accomplished when vegetative cuttings were taken from the initial selection in July 2006 and propagated further in a controlled environment in Rijsenhout, The Netherlands. The new cultivar has been found to retain its distinctive characteristics through successive propagations, although the phenotype may somewhat vary with variations in environment such as light intensity and temperature.

BRIEF DESCRIPTION OF THE DRAWINGS

The present invention of a new and distinct variety of *chrysanthemum* is shown in the accompanying drawings, the color being as nearly true as possible with color photographs of this type.

FIG. 1 shows a plant of the cultivar in full bloom.

FIG. 2 shows the various stages of bloom of the new cultivar.

2

FIG. 3 shows the various stages of foliage of the new cultivar.

DESCRIPTION OF THE INVENTION

The observations and measurements were gathered in May 2010 from plants grown in a greenhouse in Rijsenhout, The Netherlands, in a photo-periodic controlled crop under conditions generally used in commercial practice. Three cuttings were planted in a pot with a diameter of 12 cm. The greenhouse temperatures for this crop were at day-time 18.degree.C. to 25.degree. C., and at night about 20.degree. C. The photo-periodic response time in this crop was 7 weeks after an average of eight long days. After this long day period growth retardants (Alar) were applied six times in an average dose of 1.5 gram/liter water until flowering. The plants were observed (directly) during the flowering of this crop. No tests were done on disease or insect resistance or susceptibility. No tests were done on cold or drought tolerance. To show the phenotype as described 'Zanmulisa' can be planted without assimilation lightning (high pressure sodium lamps) between week 50 and week 40 of the next year under greenhouse conditions in the Netherlands. With assimilation lightning (minimum level 2500 lux) it can be planted all year round under greenhouse conditions in the Netherlands.

This new variety produces large sized daisy-type blooms with purple ray florets and a response time of 7 weeks.

From the cultivars known to inventor the most similar existing cultivar in comparison to 'Zanmulisa' is 'Dark Pink Elgon' (U.S. Plant Pat. No. 12,492). When 'Dark Pink Elgon' and 'Zanmulisa' are being compared the following difference is noticed: The difference of 'Dark Pink Elgon' and 'Zanmulisa' are (1) Inflorescence size. And (2) Color ray-florets. (1) The inflorescences of 'Dark Pink Elgon' are smaller than those of 'Zanmulisa'. (2) The ray-florets of 'Dark Pink Elgon' are pink, while those of 'Zanmulisa' are more purple.

The following is a description of the plant and characteristics that distinguish 'Zanmulisa' as a new and distinct variety.

The color designations are taken from the plant itself. Accordingly, any discrepancies between the color designations and the colors depicted in the photographs are due to

photographic tolerances. The color chart used in this description is: The Royal Horticultural Society Colour Chart, edition 2001.

TABLE 1

Botanical Description of <i>Chrysanthemum xmorifolium</i> Ramat. 'Zanmulisa'		
Bud		
Size	Medium; cross-section 6 mm, height 5 mm	5
Shape	Oblate	Diameter 6 mm
Texture	Pubescent	Reproductive Organs
Outside Color	Greyed-green 191A	
Phyllaries		
Number	22, arranged in 3 rows	Androecium Present on disc florets only
Shape	Elliptic	Stamen length 3 mm
Apex	Acute	Stamen color Yellow-green 144A
Base	Truncate	10 Anther color Yellow 3A
Margin	Entire	Pollen Present
Color	Upper surface: Green N138B	Pollen Yellow 12A
Length and width	1.2 cm; 2 mm	Gynoecium Present on both ray and disc florets
Texture	Pubescent	Style color Yellow-green 154C
Inflorescence		Style Length 3 mm
Type	Daisy	Stigma color Yellow 7A
Height	1.8 cm	15 Stigma Width 1 mm
Diameter	7 cm	Ovary Enclosed in calyx
Peduncle length	3.5 cm	Plant
Peduncle color	Green 137D	
Peduncle diameter	2 mm	20 Form Upright and branching
Peduncle texture	Pubescent	Growth habit Spherical shape
Number per branch	Approx. 5 inflorescences	Growth rate Medium
Shelf life	4 weeks	Height 24 cm
Seeds	Produced in small quantities, ovate, Greyed-brown 199A, length 1.5 mm, diameter 0.6 mm	Width 30 cm
Fragrance	Faint <i>chrysanthemum</i> odor	Stem Color Green 137C
Color		Stem Strength Strong
Center of inflorescence (disc florets)	Immature stage: Yellow Green N144B	Stem Brittleness Not brittle
Color of upper surface of the ray-florets	Mature stage: Yellow 7A	25 Stem Anthocyanin Coloration Not observed
Color of the lower surface of the ray-florets	Red-purple 71A	Internode length 1-1.5 cm
Tonality from Distance	A pot <i>mum</i> with bright purple flowers and a green center	Length of lateral branch From top to bottom 20 cm
Color of the ray-florets after aging of the plant	Red-purple 71C	Lateral branch color Green 137D
Ray florets		Lateral branch diameter 3 mm
Texture	Upper and lower side smooth	Lateral branch, attachment Medium strength
Number	20-22	30 Branching (average number of lateral branches) Prolific with 3 breaks after pinching
Shape	Elliptic	Response time 7 weeks
Apex	Dentate	Foliage
Base	Attenuate	
Cross-section	Flat	35 Leaf color Upper surface: Green 137A
Longitudinal axis of majority	Straight	Color midvein Lower surface: Green 138A
Length of corolla tube	0.4 cm	35 Color midvein Upper surface: Yellow-green 147D
Ray-floret margin	Entire	Size Lower surface: Yellow-green 148D
Ray-floret length	3-3.2 cm	Medium; length 7-9.5 cm, width 3-4.5 cm
Ray-floret width	1-1.1 cm	40 Quantity (number per lateral branch) 12
Ratio length/width	Medium	Shape Elliptic
Disc florets		Texture upper side Sparsely pubescent
Disc diameter	1.4 cm	Texture under side Pubescent
Distribution of disc florets	Abundant	Venation arrangement Palmate
Shape	Tubular	Shape of the margin Serrated
Color	Yellow 11D at apex, Yellow-green 150D at base	Shape of Base of Sinus Rounded
Length	4 mm	45 Between Lateral Lobes Margin of Sinus Between Diverging
Diameter	1 mm	Lateral Lobes Shape of Base Acute
Receptacle		Apex Mucronulate
Color	Yellow-green 145D	Petiole length 1 cm
Shape	Conical raised	50 Petiole diameter 3 mm

TABLE 1-continued

Botanical Description of <i>Chrysanthemum xmorifolium</i> Ramat. 'Zanmulisa'		
5 Height	5 mm
